DESIGN FOR A TINSEL SCARF OR SIMILAR ARTICLE

Abe Tillman, New York, N. Y.

Application July 20, 1937, Serial No. 70,535

Term of patent 3½ years

To all whom it may concern:

Be it known that I, Abe Tillman, a citizen of the United States of America, residing in city of New York, county of New York, and State of New York, have invented a new, original, and ornamental Design for a Tinsel Scarf or Similar Article, of which the following is a specification, reference being had to the accompanying drawing, forming part thereof.

The figure is a face view of a half section of a tinsel scarf or similar article showing my new design, the other half being identical with that here disclosed, arranged in proper relation to complete the scarf.

I claim:

The ornamental design for a tinsel scarf or similar article as shown and described.

ABE TILLMAN.
